(57) **CLAIM**

We claim, the ornamental design for a pair of attachment brackets, as shown and described.

DESCRIPTION

FIG. 1 is a perspective view of the attachment brackets of the present invention showing a bunk bed and a ladder in phantom view, for illustrative purposes only and form no part of the claimed design.

FIG. 2 is a perspective view showing the top and left side of one of the pair of attachment, the C-shaped bracket thereof having the same appearance from the front as from the back.

FIG. 3 is a perspective view showing the top and right side of one of the pair of attachment brackets of FIG. 2.

FIG. 4 is a perspective view showing the top and right side of the inner bracket portion of the present invention; and, FIG. 5 is a perspective view showing the left side and bottom of the inner bracket portion of FIG. 4.
